(Cl. D85—2)

To all whom it may concern:

Be it known that I, George Vincent Post, a citizen of the United States and a resident of Cincinnati, in the county of Hamilton and State of Ohio, have invented a new, original, and ornamental Design for a Combined Coaster and Ash Tray, of which the following is a specification, reference being had to the accompanying drawing, which forms a part thereof.

In the drawing:

The figure is a perspective view of a combined coaster and ash tray, showing my new design.

I claim:

The design for a combined coaster and ash tray, as shown.

GEORGE VINCENT POST.
